Patented Mar. 7, 1922.

0 Inventor
Louis V. Aronson
By his Attorney Fred C. Lischer

UNITED STATES PATENT OFFICE.

LOUIS V. ARONSON, OF NEWARK, NEW JERSEY.

BOOK OR BOX LIKE FORM SAVINGS BANK.

1,408,795.

Specification of Letters Patent. Patented Mar. 7, 1922.

Application filed May 16, 1921. Serial No. 469,776.

To all whom it may concern:

Be it known that I, LOUIS V. ARONSON, a citizen of the United States, residing in Newark, in the county of Essex and State 5 of New Jersey, have invented certain new and useful Improvements in Book or Box Like Form Savings Banks, of which the following is a specification.

The principal purpose of this invention is 10 to provide a metal receptacle for the reception and safe maintenance of money, bills and coins both being enterable, means being combined to prevent surreptitious or unauthorized extraction of the same, the device 15 constituting a savings bank and preferably made to represent the appearance of a book.

Another object is to provide a cover so arranged as to resist all attempts at opening when locked and baffle the uninitiated when 20 unlocked, the cover being so attached that it is non perceptive to casual inspection.

These and other objects, such as attractiveness in appearance, cheapness of construction and security afforded as a money 25 box for thrifty children, are attained by the novel design, combination and arrangement of parts hereinafter described and shown in the accompanying drawings, forming a material part of this disclosure, and 30 in which:—

Figure 1 is a perspective view of a money box made in accordance with the invention as completely assembled.

Figure 2 is a partial vertical sectional view 35 taken substantially in a plane represented by the line 2—2 of Fig. 1.

Figure 3 is a transverse sectional view of the assembled structure, the section being taken in a plane indicated by the line 3—3 40 of Fig. 2.

Figure 4 is an enlarged fragmentary section taken on the line 4—4 of Fig. 1.

In the drawings the numerals 10 and 11 45 designate a pair of spaced rectangular metal plates representing the covers of a conventional book, having secured between them, at a slight distance from their top and bottom edges narrow oblong plates 12 and 13, a similar plate (not shown) being at the 50 front, these plates simulating the edges of the pages or leaves of a closed book, the top and bottom plates having curved rearward extensions 12' and 13' as shown.

The front and rear plates 10 and 11 have 55 formed near their rear edges inwardly projecting, channel shaped grooves 14 and 15,

extending longitudinally and slidably engaged therein are opposed flange elements 16 and 17 formed with the arcuate cover 18 which constitutes the back of the book. 60

A spring lock, generally designated by the numeral 20, has its escutcheon 21 arranged on the cover plate 10 and is operated by the key 22 in retracting the latch bolt 23.

This lock is preferably secured in the 65 upper rear corner of the box and its bolt 23 is suited to engage in a recess 24 formed at an appropriate point in the flange 16, the bolt slipping into place when the back element 18 is in register with the side plates, 70 holding it from movement in either direction until released by the key.

As the back is neatly joined to the sides it is not readily apparent to one unfamiliar with the structure what element constitutes 75 the cover or door, the common expectation being that one or the other of the sides will open in the manner of a hinge, there being nothing to indicate that the back will slide to disclose the interior.

Money in the form of bills may be rolled 80 tightly and inserted in the opening 25 formed in the top element 10, the opening being provided with an inwardly extending annular flange 26 preventing the bill from 85 being extracted and obviously the opening is too small for the passage of coins.

Also in the top plate 10 is an elongated slot 27 for the admission of coins of varying dimensions, the recovery of which is prevented by a shutter plate 28 hinged at its ends to a bracket 29, fixed to the inner surface of the top plate 12, and carrying a stop 30 preventing the shutter from being opened more than is necessary for coin insertion, 95 the shutter being held in a normally closed position by means of a coiled spring 31 fixed to the bracket plate, its free arm 32 pressing the shutter upward as shown.

As changes of construction could be made 100 within the scope of the invention, it is intended that all matter contained in the foregoing description or shown in the accompanying drawings shall be interpreted as illustrative and not in a limiting sense. 105

Having thus described my invention, what I claim as new and desire to secure by Letters Patent, is:—

1. A toy savings bank comprising a rectangular casing simulating a book, having 110 openings for the entrance of bills and coins, a cover element slidably engaging the rear

of said casing, one of the edges of said cover having a recess, a spring impelled detent carried by said casing enterable in the recess, and key actuated means for releasing 5 said detent.

2. A toy savings bank comprising a casing simulative of a book having an open back, the edges adjacent being grooved longitudinally, a cover plate bent arcuately longitudinally, opposed flanges formed at the longitudinal edges of said cover plate, said flanges being engageable in the mentioned grooves, means for retaining said cover plate when adjusted, said retaining means being 10 releaseable and means permitting the insertion of bills and coins within said casing.

3. A toy bank comprising a hollow receptacle in appearance simulative of a book, a sliding cover plate representing the back 15 thereof, means for removably securing said plate in closed position, said receptacle having in one of its narrow sides an elongated slot through which coins may be passed, a shutter hingedly engaged interiorly of

said receptacle adapted to cover the slot, 25 a stop limiting the opening of said shutter, and a spring for normally closing said shutter.

4. A toy bank comprising a hollow receptacle in appearance simulative of a book, 30 a sliding cover plate representing the back thereof, means for removably securing said plate in closed position, said receptacle having in one of its narrow sides an elongated slot through which coins may be passed, a 35 spring actuated shutter within said receptacle adapted to close the passage through the slot, means limiting the action of said shutter, and an inwardly extending flange surrounding a circular opening adjacent 40 the mentioned slot.

This specification signed and witnessed this thirteenth day of May, 1921.

LOUIS V. ARONSON.
